TELESCOPING HOLLOW FISH POLE

Lloyd J. Le Roue, Rte. 2, P.O. Box 2360,
Wapato, Wash. 98951

Filed Mar. 16, 1970, Ser. No. 21,917

Term of patent 14 years

Int. Cl. D22—05

U.S. Cl. D22—23

FIG. 1 is a left rear top perspective view of the telescoping hollow fish pole embodying my new design in an extended position;

FIG. 2 is a right front bottom perspective view in a collapsed telescopic position;

FIG. 3 is a right front bottom perspective view in an extended position with the reel and line shown in dotted lines for illustrative purposes only.

I claim:

The ornamental design for a telescoping hollow fish pole, substantially as shown and described.
